UNITED STATES PATENT OFFICE

LESLIE BAINES HAIGH, OF ALDWYCH, LONDON, ENGLAND, ASSIGNOR TO WESTERN ELECTRIC COMPANY, INCORPORATED, OF NEW YORK, N. Y., A CORPORATION OF NEW YORK

RURAL TELEPHONE SYSTEM

Application filed March 8, 1930, Serial No. 434,244, and in Great Britain March 13, 1929.

This invention relates to a telephone system of the type in which a number of semi-automatic offices are connected together and controlled from a main or urban office.

5 The invention is particularly adaptable to a network containing a large number of small outlying offices and is therefore particularly applicable to those areas known as rural areas.

The offices in the network are arranged in 10 tandem or tree formation so that the main or urban office has access to one or more rural offices each of which in turn has access to one or more rural offices, the arrangement being continued according to the requirements 15 of the system.

The object of the invention is to provide an improved arrangement for connecting together two subscribers which may be located either in the same or in different offices in 20 the area.

According to one feature of the invention a circuit arrangement is provided for establishing a connection from one subscriber to another under the control of an operator in 25 a distant office, the connection being extended automatically from the calling subscriber to the operator over a junction line, means being provided whereby the office containing the wanted subscriber is selected by the operator and a connection extended thereto over 30 the same junction line whereupon an alternative path is automatically prepared between the two subscribers on the completion of which the common junction line is released.

More particularly the connection is extended automatically from the calling subscriber to the operator over one or more junctions and means is provided whereby the office 40 containing the wanted subscriber is selected by the operator and the wanted subscriber is connected to such operator over at least one of the aforesaid junctions, whereupon an alternative path is automatically prepared between the two subscribers if necessary over 45 one or more of the other junctions previously employed on the completion of which the common junctions may be released.

If the two subscribers should be located in 50 the same office a direct alternative path may

be prepared between them and the common junction line or lines over which the connection was set up may be automatically released as before.

According to a further feature of the invention the path from the operator to the wanted subscriber employs at each office en route, common apparatus, whereas the alternative path between the two subscribers is completed independently of such common 55 apparatus.

The call is preferably routed from the calling subscriber to the operator over one or more junction switches, one of which is located at each office en route after which the 60 connection is routed from the operator to the wanted subscriber through one or more registering mechanisms, one of which may be located at each office en route. One or more link circuits each having a plurality of finder 65 switches may also be provided at each office, the arrangement being such that the switches of one such link circuit in the office which is furthest from the main office and which also has access to the calling and wanted offices set 70 themselves in accordance with the setting of the junction switch and the registering mechanism respectively employed at that office, thereby preparing an alternative path between the calling and called subscribers. 75

One or more junction circuits each having a finder switch may also be provided at each office, the arrangement being such that the switch of one such junction circuit in each of the offices between the office which is furthest from the main office and which also has access to the calling and wanted offices, sets itself in accordance with the setting of the registering mechanism in that office thereby further preparing an alternative 85 path between the calling and wanted subscribers.

Moreover the aforesaid junction circuit may be the same as those employed for extending a connection from a calling subscriber to an operator. 90

The arrangement may be such that when the alternative path between the two subscribers is completed, both the subscribers are automatically disconnected from the 100

operator at the main office who is thus prevented from over-hearing any conversation between the two subscribers.

An arrangement is also provided whereby should a subscriber originate a call and the operator not answer promptly, he may replace his receiver and await recall, the call being arranged to proceed until the operator answers.

10 An arrangement is also provided whereby should a subscriber originate a call and abandon it without replacing his receiver, means is provided whereby the operator can forcibly break down the connection.

15 Arrangements are also provided for trunk offering.

The invention will be more completely understood from the following detailed description which is given in conjunction with 20 the accompanying drawings in which

Fig. 1 shows a link circuit for use at an end rural office for completing an alternative path between two subscribers.

Fig. 2 shows a two-way junction circuit. 25 Figs. 3 and 4 show a register circuit for use at an end rural office.

Fig. 5 shows a tandem link circuit.

Fig. 6 shows a tandem junction circuit.

30 Figs. 7 and 8 show a register circuit for use at a tandem rural office.

Fig. 9 shows the termination of a tandem junction from a rural office at the urban office.

Fig. 10 shows a subscriber's station and 35 line circuit.

Fig. 11 shows a tandem line circuit.

Fig. 12 represents a layout of a number of 40 the offices in the tandem formation with the various elements forming the offices shown diagrammatically.

Figs. 13 to 17 show the manner in which Figs. 1 to 11 are to be arranged in connection with each of the calls to be traced herein-after.

45 It is thought that the invention will be best understood from first considering the layout shown in Figure 12.

In Figure 12 an urban or main office is shown at D with one or more main junctions 50 extending to a tandem rural office A. The tandem rural office A has a number of outlets, some of which extend to the subscribers located on the office A others of which extend to a similar tandem rural office such as B 55 while others extend to an end rural office such as BB. Similarly exchange B has a number of outlets similar to those of A extending either to local subscribers or to another outlying end rural office such as C and a group 60 of tandem junctions connecting to the tandem rural office A which corresponds with the group of main junctions connecting the exchange A to the urban office D.

A brief description of the progress of a 65 call between subscribers located on any of

the four rural offices or on the main office D will now be given.

In the case of a call from subscriber S2 on office B to subscriber S1 on the urban office D the subscriber S2 initiates the call by 70 turning the handle of his magneto, whereupon a line relay in the line circuit SLB responds and a free junction finder JSB sets itself on the calling line. A line relay in the tandem line circuit TLB in exchange A then 75 operates and a free junction finder switch JSA sets itself on the line taken into use. A supervisory signal then operates in front of the operator at the main office D who then completes the connection manually to the 80 wanted subscriber S1 in the usual way.

If subscriber S2 in office B had wanted to extend the connection to subscriber S3 in the same office the connection to the operator in the main office D would be established in the 85 same way as previously described. The operator, however, on receiving the call connects by means of a set-up plug the junction circuit JA to the register RA of office A. The operator then dials the digit corresponding to 90 the group of tandem junctions JLB whereupon on the line selector RSA of the register RA sets itself on the tandem line TLB taken into use and the junction circuit JB is connected to the register RB instead of to the junction 95 finder switch JSB. The operator then dials through the register RA into the register RB the wanted subscriber's number (two digits) whereupon the line selector RSB of the register RB is set on to the wanted line leading 100 to the subscriber S3 and tests the line and signals to the operator at office D. At this stage the finder switch SB1 of the link LB is positioned on terminals corresponding to those assumed by the switch JSB, that is to say, on the line of the subscriber S2. The switch SB2 of the link LB is positioned on the terminal corresponding to that assumed by the switch RSB, that is to say on the line 105 leading to the subscriber S3. A link circuit is thus prepared between the subscribers over the link LB which is independent of the register and the lines extending back to the main office. The operator then rings subscriber S3 through the registers RA and RB. 110 When subscriber S3 responds the connection is established to subscriber S2 through the link LB and the switches SB1 and SB2 and a signal is transmitted to the operator at office D who removes the set up plug whereupon 115 the registers RA and RB release in turn. When the operator removes the regular plug the junction circuits JA and JB release in turn.

In the case of the extension of a call from a subscriber S2 in office B to a subscriber S4 in office BB the connection is set up to the operator in the office D in the same way as before. The operator inserts her set-up plug 125 and dials into the register RA the digit cor- 130

responding to the group of tandem junctions JLBB leading to the office BB. The operator dials through the register RA into the register RBB the wanted subscriber's number. The line selector RSBB of the register RBB is set on to the line of subscriber S4 which is tested and a signal is transmitted to the operator. At this stage the finder switch JSB of the junction circuit is already positioned on the calling line. The switch JSBB of the junction circuit of office BB is positioned on the terminal corresponding to those assumed by the switch RSBB, that is to say on the wanted line leading to subscriber S4. The finder switch SA1 of the link LA is positioned on a terminal corresponding to that assumed by the switch JSA, that is to say, on the line TLB while the switch SA2 is positioned on the terminals corresponding to those assumed by the switch RSA, that is to say on the line TLBB. The operator then rings subscriber S4 via the registers RA and RBB. When the subscriber S4 responds the register RBB is released and the junction circuit JBB is connected to the switch JSBB and a connection is established via the junction circuit JB, the link LA and the junction circuit JBB whereupon a signal is transmitted to the operator. The operator takes out the set up plug whereupon the register RA releases as before and when she removes the regular plug the junction circuit JA is released.

In the case of a connection being extended from subscriber S2 in office B to subscriber S5 in office C the connection is established in the same way as a connection from subscriber S2 to subscriber S3 until the junction circuit JB is connected to the register RB. The operator then dials through the register RA into RB a digit corresponding to the group of tandem junctions JLC leading to office C. The register RSB then hunts for a free junction in this group and the junction circuit JC is connected to the register circuit RC. The operator then dials through the registers RA and RB into the register RC the wanted subscriber's number. The line selector RSC in the register RC is set on to the wanted line (S5) which it tests and then signals to the operator at office D. The finder switch SB1 of office B is set onto the terminals corresponding to those assumed by the junction switch JSB, that is to say, on the line JLC leading to office C. The junction switch JSC is set on to the terminals of those assumed by the line selector RSC, that is to say on the wanted line S5. The operator then transmits ringing current to S5 via the registers RA, RB and RC. When the subscriber S5 responds the register RC releases and the junction circuit JC is con-

nected to the switch JSC instead of to the register RC whereupon a connection is established via the link LB and the junction circuit JC and a signal is transmitted to the operator. The operator removes her set-up plug whereupon the registers RA and RB release and when she removes the regular plug the junction circuits JA and JB release. 70

In the case of a connection being extended from subscriber S1 in office D to the subscriber S4 in office BB, on the call arriving in front of the operator she inserts both plugs in the jacks of a disengaged junction JLA leading to office A whereupon the junction circuit JA is connected to the register RA. The operator dials into the register RA a digit corresponding to the group of tandem junctions JLBB. The line selector RSA of the register RA hunts for a free junction in this group and the junction circuit JBB is connected to the register RBB. The operator dials through the register RA into the register RBB the wanted subscriber's number whereupon the line selector RSBB of the register RBB is set on to the wanted line S4 which is tested and a signal is transmitted to the operator. The junction switch JSA is set on to terminals corresponding to those assumed by the line selector RSA that is to say, on the line JLBB while the junction switch JSBB is set on to terminals corresponding to those assumed by the line selector RSBB, that is to say on to the wanted line S4. The operator then rings the wanted line S4 via the registers RA and RBB. When 100 the called subscriber S4 responds the register RBB is released and the junction circuit JBB is connected to the junction switch JSBB. When the operator removes the set-up plug register RA is released and the junction circuit JA is connected to the switch JSA and a through connection is thus established. 95

Referring now to the circuits shown in Figs. 1-9, in order adequately to describe the operation of the system in the establishment of the various kinds of local calls, that is, calls between subscribers within the rural network, it will be convenient to consider operations involving the 4 rural offices diagrammatically shown in Fig. 12. These consist of an office A directly accessible to an urban manual office D and therefore having no office code; two offices B1 and B2, connected to A by groups of tandem junctions, and having the office codes 3 and 4 respectively; and an office C, connected by a group of tandem junctions to B1 and having the office code 34. Since both offices A and B1 are both tandem offices, only one showing has been made and Figs. 5 to 8 are repeated in the layout of Figs. 13 to 17. There are two groups of tandem lines on A so that relays 733 and 734, which identify these groups, are equipped but relay 732 is unnecessary. There is one group only on B1 so that relay 734 is 125 130

assumed to be equipped in dialing with that office and relays 732 and 733 are unnecessary. Since offices B2 and C are both non-tandem offices, they may both be considered to be wired according to Figs. 1 to 4.

Call I

The establishment of a call from subscriber 361 at office B1 to an urban subscriber will first be described.

- 10 This call involves offices B1, A and D, a tandem junction between B1 and A and a main junction between A and D. For this call Figs. 5 to 11 will be arranged as shown 15 in Fig. 13. To originate a call the subscriber turns his hand generator 1001 and then removes the receiver from the switchhook. The generator 1001 is connected across the line and the A. C. current operates the subscriber's line relay 1002 at exchange B1. Relay 1002 locks through its middle and right winding, over its two contacts and conductor 20 504 in series with the common start relay 815 in the register (Figs. 7 and 8) which 25 also operates. Battery potential from relay 815 is connected to conductor 503 and terminals such as terminal 604 individual to this line in the banks of all the junction finders in order to identify it. At the contact of 30 relay 815, relay 802 being assumed normal, ground is connected to the start chain, and operates relay 619 in the first disengaged junction (Fig. 6). If a junction is busy or otherwise out of service, the start chain is 35 extended over conductor 626 to the next junction via key 625, or contact 11 of relay 611, or contact 6 of relay 608, or contact 5 of relay 602. On operating relay 619 locks independently of contact 7 of relay 608 at contact 40 40 of relay 619. Relay 619 closes a circuit for the magnet 624 of the junction switch 610, via its own interrupter contacts, at contact 1 of relay 619, and also a testing circuit through the lower winding of relay 608 at contact 2 of relay 619. The junction switch 45 begins to hunt and when the calling line is found, relay 608 operates to the battery identifying the calling line on terminal 604. Relay 608 opens the drive at its 8th contact, 50 locks over its third contact to ground at contact 8 of relay 620, and connects ground to the test wiper at its fifth contact, short circuiting relay 1002. Relay 608 extends the start chain to the next junction at its 6th contact and connects battery through the winding of relay 601 to the negative leg of the junction at its 4th contact. Relay 102 releases and opens the circuit of relay 815, which also releases, followed by relay 619. 55 60 At the office B1 we have, therefore, the following conditions:—The wipers of the junction switch 610 are resting on the terminals of the calling tandem line which, in turn, has the wipers of its own switch at office B1 resting on the terminals of the calling subscriber's line. Relay 608 is operated and locked to ground at contact 7 of relay 620. Relay 1101 is operated to ground at contact 5 of relay 608 which also busies the tandem line. Relays 620 and 603 are operated to ground at contact 2 of relay 620. Battery is connected to the negative leg of the junction through relay 601 to signal the call at the urban office D. 65

at contact 8 of relay 620 which is a back contact. The calling line is rendered busy to a testing selector by the ground connected to terminal 604 at contact 5 of relay 608. Battery is connected to the negative leg of the junction to extend the call to office A, and relays 617 and 618 are waiting in readiness to accept a battery from office A over the positive leg.

The junction appears at A as "tandem line" 75 1100, and relay 1102 operates to the battery on the negative leg. Relay 601 at office B1 does not operate in this circuit owing to the high resistance of relay 1102. At contact 1 of relay 1102 a circuit is closed for 80 relay 815 in the register at this office. At contact 4 of relay 1102 battery is removed from the test wire 509 leading to the line selector 700 causing the line to test busy, and connected to the terminal 604 of this line 85 to identify it. Relay 815 closes a circuit for relay 619 in the first disengaged junction as before, and relay 619 drives the junction switch 610 and closes a test circuit. When the calling tandem line is found, relay 608 90 operates, locks to ground at contact 3 of relay 619, trips the switch, extends the start chain, connects battery to the negative leg, and grounds the terminal 604, operating relay 1101. Relay 1101 locks over its 4th contact independently of relay 1102, to this ground, and disconnects relay 1102 from the line at its first contact. Relay 1102 releases, followed by relays 815 and 619. Relays 1102 and 619 are slow to release due to slugs. During the releasing time of relay 1102 ground is connected to the conductor 505 of the tandem line over contact 2 of relay 1102 and contact 2 of relay 1101, and until relay 619 100 has released, relay 620 is connected to terminal 605 over contact 5 of relay 619. Relay 620, therefore, operates during this fleeting condition and locks over contact 9 of relay 608 to ground at its second contact. Relay 603 then operates to this ground via 105 contact 2 of relay 602 and contact 2 of relay 608. With relays 603 and 620 both operated, relay 608 locks independently of relay 619 to ground at contact 7 of relay 620.

At office A we have, therefore, the following conditions:—The wipers of the junction switch 610 are resting on the terminals of the calling tandem line which, in turn, has the wipers of its own switch at office B1 resting on the terminals of the calling subscriber's 112 line. Relay 608 is operated and locked to ground at contact 7 of relay 620. Relay 1101 is operated to ground at contact 5 of relay 608 which also busies the tandem line. Relays 620 and 603 are operated to ground at contact 2 of relay 620. Battery is connected to the negative leg of the junction through relay 601 to signal the call at the urban office D.

At office D relay 900 operates to the battery on the negative leg and closes a circuit for the 13

- calling lamp 901 at its second contact. Relay 601 at A does not, however, operate owing to the high resistance of relay 900. To answer the call, the operator inserts a plug of one of her regular cords in the talk jack 902 and relay 903 operates. Relay 903 opens the lamp circuit at its 5th contact and connects weak battery through retard coil 904 to the positive leg of the junction at its third contact. At A, relay 617 operates to this battery, but not relay 618. A balancing weak battery through the left winding of relay 900 is connected at contact 2 of relay 903 to the negative leg and relay 900 releases. Relay 617 operates relay 602 which removes the calling battery from the negative leg at its 8th contact, connecting the negative leg over its 7th contact also to the winding of relay 617 in order to balance the bridge and reoperate relay 900. At the first and third contacts of relay 602 the negative and positive legs are extended to the tandem line. Relay 603 releases, but relay 608 is now held by ground at the 4th contact of relay 602. Weak battery 25 through retard cord 616 is connected to the positive leg at contact 1 of relay 602 and operates relay 617 (but not relay 618) at office B1. As at A, relay 617 at B1 operates relay 602, which removes battery from the negative leg of the junction, balances the bridge and also holds relay 608. Relay 602 at B1 extends the talking connection from the operator to the calling subscriber.
- We now have the following conditions:—
- 35 Weak battery connected at D to the positive leg holds relay 617 at A which, in turn, holds relay 602, which holds relay 608. Weak battery via the first contact of relay 602 at A holds relay 617 at B1, which, in turn, holds relay 602, which holds relay 608. The train is thus held under the control of the operator. If the receiver is still on the switchhook at the sub-station, ground is connected to the negative leg through the sub-station ringer.
- 40 This ground operates relay 603 at B1. At its 5th contact (relay 620 being normal at B1) relay 603 removes ground from the negative leg of the tandem junction, and relay 603 at A cannot operate. At A with relay 603 normal and relay 620 operated, ground is kept from the negative leg of the main junction, and relay 900 at D is normal, lighting the supervisory lamp 901 at contact 1 of relay 900. If, on the other hand, the receiver is off the rest, relay 603 at B is normal, relay 603 at A is operated, relay 900 at D is operated and the supervisory lamp is out. Positive supervision between the subscriber and the operator is, therefore provided.
- 45 Should the subscriber not remove his receiver immediately, the operator can ring him. To do this, the revert plug of the special operating cord 905 is inserted in the operate jack 906, and the ring key is thrown.
- 50 Ground is thereby connected to the sleeve of the plug, and relay 907 operates, disconnecting the main junction from coil 904 and relay 900, and connecting it to the tip and ring of the special cord. The tip is connected to strong battery, which holds relay 617 at A 70 and in addition operates relay 618. At the second contact of relay 618 (relay 620 being operated) strong battery is connected to the positive leg of the tandem junction, and this holds relay 617 at B1 and operates relay 618. 75 Contact 9 of relay 620 prevents a discontinuity while relay 618 is changing over. At office B1 (relay 620 being unoperated) relay 618 joins the positive and negative legs of the subscriber's line at contact 2. 80
- Returning to A, relay 618 disconnects relay 603 from the negative leg of the tandem line at contact 4. Ground through relays 617 and 601 is already disconnected at contact 4 of relay 603 (relay 620 being operated) 85 from the negative leg of the main junction. We have, therefore, a direct connection, without any branches, between the ring of the plug at D and the negative leg of the tandem junction. At B1, relay 618 disconnects relay 603 from the negative leg of the subscriber's line at its 4th contact, but relay 603 remains operated to ground at contact 1 of relay 620. Relay 603 does not release during the change-over owing to the damping effect of the shunt over its third contact. Ground through relays 617 and 601 is already removed from the negative leg at contact 5 of relay 603 (relay 620 being unoperated). Here also we have a direct connection without any branches, between the negative leg of the tandem junction and the negative leg of the subscriber's line, but in this case, the positive leg of the subscriber's line is also connected. When the ring key at D 100 is thrown, grounded ringing current is connected to the ring of the revert plug and this current has a direct path to ground through the bell of the subset, which may be connected either between the negative leg and ground or across the line with its middle point grounded. When the ring key is restored, relay 907 at D releases, followed in turn by relay 618 at A and relay 618 at B1. In the first silent period after the subscriber has removed his receiver, relay 603 at B1 releases, relay 603 at A operates, relay 900 at D operates, the supervisory lamp 901 goes out, and the operator will remove 110 the revert plug.
- 115 By throwing the speak key in her regular cord 908, the operator can converse with the calling subscriber and will complete his urban call in the usual manner.
- 120 At the end of the call, the operator receives a positive "clear" signal, as already explained. On the withdrawal of the plug, relay 903 at D releases, removing battery from the positive leg and releasing relays 617, 602, 125 130

608, 1101 and 620 at A and relays 617, 602, 608 and 603 at B.

It should be noticed that if the operator withdraws the plug before the subscriber has replaced his receiver, the connection at A and B1 is not broken down for, at A, relay 608 is held via contact 2 of relay 603 and contact 7 of relay 620, both of which are operated independently of relay 602 and at B1, relay 608 is held over contact 1 of relay 603 and contact 8 of relay 620, both being unoperated. On the release of relay 903 at D with relay 900 still operated, the calling lamp again glows, informing the operator of her mistake. Thus it will be seen that the connection is normally held until the subscriber has replaced his receiver and the operator has withdrawn the plug in that order.

Should, however, the rural subscriber not replace his receiver within a reasonable time after the urban subscriber has cleared, the operator can forcibly release the connection. To do this, she removes the regular plug, inserts the release plug of the operating cord in the operate jack 906, and throws the release key. Ground is connected to the sleeve and operates relay 907, which disconnects the main junction from coil 904 and relay 900 and connects it to the tip and ring of the cord. The tip is connected to strong battery which operates relay 617 at A and in addition operates relay 618. At contact 2 of relay 618 (relay 620 being operated), strong battery is connected to the positive leg of the tandem junction and this operates both relay 617 and relay 618 at B1. Relay 618 at A disconnects relay 603 from the negative leg of the tandem junction at contact 4 and relay 603 releases. At B1 relay 618 disconnects relay 603 from the negative leg of the subscriber's line at contact 4, connects it to ground at contact 1 of relay 620, and relay 603 operates. At A and B1 relay 608 is now holding to ground at contact 4 of relay 602, the alternative holding circuit over contacts of relays 603 and 620 being open at both offices. The operator then restores the release key and relay 907 releases, removing battery from the positive leg of the main junction; relays 617 and 618 at A release. Relay 617 releases relay 602, which releases relay 608, which releases relay 620. Either relay 602 or relay 618 removes battery from the positive leg of the tandem junction, releasing relays 617 and 618 at B1. Relay 617 releases relay 602 which releases relay 608, relay 602 or relay 618 releases relay 603. Relay 603 at B1 is sufficiently slow to release, due to the shunt over its third contact, to allow relay 608 to release before reclosing its alternative locking circuit. When relay 603 at B1 has restored, a circuit is closed for relay 603 at A. Similarly relay 603 at A is sufficiently slow to operate to allow relay 608 to release before its alternative locking circuit is closed. The connec-

tion at both offices has thus been forcibly released. Although the subscriber has not yet replaced his receiver, another call is not originated, since his line relay at B1 requires generator current to operate it.

70

Call II

The establishment of a call from subscriber 361 to subscriber 352 at the same office will now be described.

75

This call involves office B1 only, in the final connection, and after the establishment of this call the operator at D will release the junction between D and A and between A and B1 which have been used. Figs. 5 to 11 will be used as shown in Fig. 14.

80

Subscriber 361 originates the call as already described by turning his generator and lifting his receiver. The call proceeds as soon as junctions are available, via B1 and A to D and the calling lamp lights before the operator.

85

The operator inserts the plug of one of her regular cords in the junction talk jack 902 and receives the subscriber's requirements. The call is for subscriber 352, that is, for a subscriber within the same rural network, and is therefore established by the operator by means of her special operating cord.

90

The operator inserts the set-up plug of this cord in the operate jack 906 of the junction over which the call has arrived. Ground on the sleeve operates relay 907 which at contact 6 disconnects the calling lamp 901 and lights a guard lamp 909. At contacts 1 and 4 the positive and negative legs of the junction are disconnected from the talk jack 902 and coil 904 and relay 900 and at contacts 2 and 3 are connected instead to the tip and ring of the operate jack and thence to the operating cord. The tip of this cord is connected to weak battery which is kept on the positive leg and holds relay 617 at A operated. The ring of this cord is connected to strong battery which causes relay 601 at A to operate. At contact 2 of relay 601 a circuit is closed for the impulse accepting relay 701 in the register (Fig. 7) providing the register switch is in its home position. If the register is off normal, due to the operator reinserting the plug immediately after releasing a previous call, relay 701 will not operate and a supervisory signal will be given to the operator. This delay in the operation of relay 701 will not normally occur and will in any case be of short duration unless the register is out of order. Relay 701 operates and closes a circuit for relay 802 at its second contact. At contact 3 of relay 802 ground is removed from the contact of relay 815 so that no junction finder can operate while the register is in the use, and ground is connected over contact 1 of relay 601 in the junction taken into use to relay 611, which operates. Relay 611 locks

115

120

125

130

at its 13th contact independently of relay 601. At the 7th and 8th contacts of relay 611 the holding circuit of relay 608 is transferred from relay 602 to relay 706. At contacts 3 and 4 of relay 611 the negative leg of the junction is disconnected from relay 601, which releases, and is connected to relay 701, which now holds over this circuit independently of relay 601. At contact 1 of relay 611, the positive leg is disconnected from relay 617 which releases, followed by relay 602. Relay 602 at contact 1 disconnects the battery which is holding relay 617 at B1 and relay 617 releases, followed by relay 602 at B1, but the junction circuit is not released because relay 617 has restored before the subscriber has hung up, as already explained. At contact 1 of relay 802 at A, an alternative ground is provided for relay 701 so that relay 701 will not release when the selector leaves its home position. The positive leg is now disconnected, so that the supervisory lamp goes out.

We now have the following conditions:—

25 At B1, relay 608 is locked over its third contact, contact 8 of relay 611, contact 1 of relay 603 and contact 8 of relay 620. The junction is busied by contact 6 of relay 608. The calling subscriber's line is busied by contact 5 of relay 608. At A, relay 608 is locked over contact 3 of relay 608, contact 7 of relay 611, contact 3 of relay 706. The calling tandem line is busied, and relay 1101 is held, by contact 5 of relay 608. The junction is busied by contact 11 of relay 611. Relay 620 is held by contact 9 of relay 608. The operator is no longer connected to the calling party. Since she is now concerned in establishing connection with the called party and is using the same junction, this is a desirable condition. The supervisory lamp and calling lamp are both out, but the guard lamp warns the operator that a register is being held. Battery over the dial springs in the cord holds relay 701 which holds relay 802, which holds relay 611.

The operator then proceeds to dial the digits of the wanted number. Relay 701 responds to the impulses of the first digit, and at each break closes a circuit for relays 822 and 703 over contact 3 of relay 701, contact 5 of relay 802, contact 8 of relay 725, contact 1 of relay 710, contact 1 of relay 805 and contact 4 of relay 701. Relay 822 repeats the impulses to the driving magnet 702 of the selector. Relay 703 being slow-to-release remains operated until the end of the digit and operates relay 827 at contact 1.

If one of the digits 1, 2, 8, 9 or 0 has been dialed in error, no connection can result. (It is assumed that relay 732 is not equipped and that contact 2 of relay 814 is connected to terminal 72). If 2 has been dialed, the selector 700 is resting on the terminals of line 72 and when relay 703 releases a circuit

is closed for relay 805 over contact 2 of relay 703, contact 13 of relay 724, wiper 716, contact of relay 814, contact 2 and lower winding of relay 805, contact 8 of relay 706, contact 4 of relay 802. If 1, 8, 9 or 0 has been dialed, a circuit for relay 822 is closed at contact 3 of relay 827 as soon as relay 827 releases and the selector drives until line 72 or 61 has been reached, when relay 805 operates in a similar circuit. Relay 805 locks out in either case over its third contact and opens the drive at its first contact. The opening of contact 1 of relay 805 also renders further dialing ineffective. Relay 805 closes a circuit for relay 712 over contact 4 of relay 805, contact 7 of relay 809, winding of relay 701, and contact of relay 712, and as relay 712 interrupts its own circuit a tone is produced. This is induced into the line winding of relay 701 and transmitted over the junction to the operator, who then removes the set-up plug. Strong battery is disconnected from the negative leg and on the release of relay 907, weak battery is replaced on both legs. Relay 701 at A releases, followed after an interval by relay 802, which in turn releases relay 805 and relay 611 and closes a homing circuit for the selector 700, controlled by relay 822, over wiper 715, interrupter contact of magnet 702, contact 6 of relay 802, contact 8 of relay 725, contact 1 of relay 710, and contact 1 of relay 805. Relay 703 also operates over contact 4 of relay 701, operates relay 827 and relay 827 prevents any other finder from stepping at its 6th contact. When the selector 700 is again in its home position the register has been completely released. The operator will then reinsert the set up plug and dial the number again.

Assuming that 3 has been correctly dialed, the selector has now taken 3 steps and its wipers are standing on the terminals of line 73. At the end of the digit, when relay 703 releases, a circuit is closed for relay 733 over contact 2 of relay 703, contact 13 of relay 724, wiper 716, contact 7 of relay 724, upper winding of relay 733, contact 6 of relay 814, and contact 4 of relay 802. Relay 733 locks over its second contact and operates relay 724 at its third contact. At its 4th contact, relay 708 is connected to the terminals of brush 716 belonging to the tandem lines in the "3" group that is, with typical wiring as shown, lines 54, 55 and 56. Relay 724 operates relay 731 over contact 6 of relay 724, contact 7 of relay 726 and contact 7 of relay 708, and relay 731 at its 2nd contact connects the steer wires of all the tandem lines to contacts of relays 733 or 734. Relay 733 only is operated and at its first contact extends the steer wires of the lines in the "3" group to the lower winding of relay 726. Over contact 6 of relay 724, contact 1 of relay 731 and contact 6 of re-

70

75

115

120

125

130

lay 611, battery is connected to terminal 605 and wire 505 of the calling tandem line, which is in the "3" group since the calling subscriber's number is 361, and this battery is extended over conductor 506 contact 2 of relay 731, contact 1 of relay 733, winding of relay 726, contact 9 of relay 611, contact 3 of relay 608, contact 7 of relay 611, to ground at contact 3 of relay 706, so that relay 726 operates. Relay 726 locks at its first contact, disconnects relay 731 at its 7th contact and relay 731 releases. When relay 703 has restored, relay 827 releases. Relay 724 also closes a driving circuit for the selector 700 controlled by relay 822 over wiper 715, interrupter contact of magnet 702, contact 4 of relay 724, contact 10 of relay 708, contact 1 of relay 710, and contact 1 of relay 805. The selector is now searching for the calling tandem line and when this has been reached a circuit is closed for the tripping relay 708 over contact 4 of relay 802, lower winding and 4th contact of relay 708, contact 4 of relay 733, wiper 716 and its associated contact, contact 12 of relay 724, contact 2 of relay 726, wiper 705 of selector 700, steer wire 506, terminal 605 and its associated wiper of finder 610, contact 6 of relay 611, contact 7 of relay 726 and contact 6 of relay 724. At its 7th, 14th, 8th and 3rd contacts relay 724 disconnects relays 733, 734, 708 and 813 and 814 respectively, from terminals over which wiper 716 passes during this search. Relay 708 opens the drive at its 10th contact and locks out at its 5th contact. It also closes a circuit for relay 725 over contact 5 of relay 805, contact 3 of relay 708, contact 9 of relay 724, and contact 5 of relay 717, and for relay 804 over contact 6 of relay 725. Relay 725 holds over contact 6 of relay 726. At contact 7 of relay 725 ground is placed on wiper 704 to hold relay 1101 of the calling tandem line 1100. Over contact 2 of relay 804, contact 5 and 2 of relay 725 weak battery is connected to the positive leg of the tandem line through the non-inductive winding of relay 823 and operates relay 617 at B1. Relay 617 operates relay 602 which connects relay 617 and ground also to the negative leg at its 7th contact. Over contact 9 of relay 725, contact 2 of relay 809 and contact 1 of relay 701, strong battery is connected to the negative leg and this operates relay 601 at B1 and associates the register with the tandem junction in precisely the same manner as the register at A was associated with the main junction. Relay 725 operates slowly thus giving relay 804 a soak before it opens its circuit at its 6th contact. Relay 804 is slow to release and keeps the operative windings of relay 823 off the positive leg at its first contact until relay 611 has operated at B1. On the release of relay 804, relay 823 is connected to the positive leg and awaits a ground signal from B1.

The operator then dials the second digit 5. Relay 701 at A responds but does not step the register because the energizing circuit of relay 822 is open at the 8th contact of relay 725, nor does relay 703 operate. The impulses are repeated to B1 over contact 1 of relay 701, which is shunted by a spark quench consisting of a 2 mf. condenser in series with 100 ω , by opening the circuit in which relay 701 is holding at B1. Relay 701 responds and steps the selector at this exchange. Relays 703 and 827 operate during the train of impulses. The selector has now taken 5 steps and is resting on the terminals of line 75. When relay 827 releases a circuit is closed for relay 708 over contact 2 of relay 703, contact 13 of relay 724, wiper 716, contact 8 of relay 724, contact 5 of relay 827, contact 4 and the lower winding of relay 708, and contact 4 of relay 802, and relay 708 operates and locks over its 5th contact. At contact 10 of relay 708 the drive circuit for the selector 700 is kept open so that the selector remains on the terminals of line 75, that is, at the beginning of the 50's group. At contact 1 of relay 708 a circuit is closed for relay 816 over contact 9 of relay 816, contact 1 of relay 708, contact 8 of relay 726, contact 2 of relay 717, contact 9 of relay 611, contact 3 of relay 608, contact 7 of relay 611, contact 3 of relay 706. Relay 816 operates and locks over its 10th contact. At contact 13 of relay 816 a test is made to determine whether there is at B1 a disengaged link. If the first choice link (Fig. 5) is engaged or out of service, the chain is closed over contact 3 of relay 508 or key 510, and relay 807 receives a circuit over contact 4 of relay 802, contact 8 of relay 706, contact 13 of relay 816, contact 3 of relay 508 or key 510, and contact 2 of relay 807. Relay 807 operates, locks out over its first contact and at its remaining armatures changes over to the second choice link. If this also is engaged, the chain is further extended over the contact of relay 508 or key 510 of the second link to relay 805 and this relay operates, locking out over its 3rd contact. Relay 805 closes a tone-producing circuit at its 4th contact and the operator is informed either that she has dialed incorrectly or that there is no link available, and she will release the registers by removing the set-up plug. If she is satisfied that the number has so far been correctly dialed, she will inform the calling party, who has been reconnected to her by the operation of relay 617, and relay 602 at A and B1, that there is no outlet available. Otherwise, she will dial again.

If the operator hears no tone at this stage, she dials the third digit 2. Relay 701 at A responds and repeats the impulses to relay 701 at B1 and the latter steps the selector. Relays 703 and 827 at B1 are energized during the train of impulses. Relay 827 closes a circuit for relay 804 over contact 2 of relay

827, contact 10 of relay 724, contact 3 of relay 708 and contact 5 of relay 805.

It will be observed that with typical wiring as shown (and relay 732 not equipped), 5 51, 52 and 53 are the only lines available in the 50's, and accordingly contact 8 of relay 708 will be connected to the terminal of line 54. If 54 or above has been dialed in error, relay 805 operates, as soon as line 54 is 10 reached, over contact 9 of relay 708, contact 13 of relay 724, wiper 716, contact 8 of relay 708, contact 5 of relay 724, contact 2 and winding of relay 805, contact 8 of relay 703 and contact 4 of relay 802. Relay 805 locks 15 out over its third contact, stops the selector and renders further dialing ineffective at its first contact and closes a tone producing circuit at its 4th contact. Tone at this stage informs the operator that she has dialed incorrectly, and she will release the registers and dial again.

Assuming that 2 has been correctly dialed, at the end of the digit the wipers are resting on the terminals of line 52, that is, of the 25 wanted line, and relays 703, 827 and 804 release in turn. During the releasing period of relay 804 a circuit is closed for relay 811 over contact 4 of relay 804, contact 1 of relay 827, contact 10 of relay 724, contact 3 of relay 708, and contact 5 of relay 805. Relay 811 operates relay 710 over contact 4 of relay 811 and contact 4 of relay 802. At contact 1 of relay 710 the stepping circuit for the selector is opened so that subsequent dialing is ineffective. 30 At contact 7 of relay 710 ground is connected through the winding of relay 809 to the positive leg of the tandem junction, operating relay 823 at A. Relay 823 operates relay 710. Relay 710 operates relay 706 over its 5th contact and contact 7 of relay 811 and relay 706 locks over its 7th contact; also relay 710 connects ground through the winding of relay 809 to the positive leg of the main junction and this operates a relay in the set-up cord at D, lighting the supervisory lamp to inform the operator that dialing and testing of the wanted line are complete. When relay 804 releases, relay 811 is connected over contact 5 of relay 804, contact 2 of relay 708 and contact 6 of relay 811 to brush 35 704.

If the wanted line is busy, there is ground on the test terminal from the associated link or junction and relay 811 remains operated. 40 Relay 811 closes a tone producing circuit over contact 5 of relay 811, contact 3 of relay 804, contact 7 of relay 809, through the winding of relays 701 and 712 by way of the interrupter contact of relay 712 and the tone is transmitted to the operator. Tone and lamp together inform the operator that the wanted line is engaged. The operator can then either release the registers and inform the calling party that his number is engaged, or 45 she can "offer" the call. To do this she con-

nects low resistance battery direct to the tip, and the strong battery operates relay 809 at A. At contact 5 of relay 809, relay 701 is removed from the negative leg and is connected to a holding battery. The tone circuit is opened at the 7th contact of relay 809. At 50 contact 8 of relay 809 the low resistance winding of relay 823 is connected to the positive leg of the tandem junction and operates relay 809 at B1. Relay 809 at B1 removes relay 701 from the negative leg as at A, and at contacts 1 and 3 connects the tandem junction to the wanted line. The operator can then offer the call to the wanted subscriber and, should he accept, will instruct him to replace his receiver. She will then restore the key, releasing relay 809 at both exchanges, and will again hear tone. When the wanted subscriber hangs up, his existing connection is broken down and ground is removed from his test terminal and his line is now free.

If the wanted line is free, relay 811 is deprived of its circuit and releases, disconnecting the tone at its 5th contact and connecting relay 710 over contact 3 of relay 811, contact 2 of the relay 710, and contact 7 of relay 717 to ground at contact 4 of relay 802. Relay 703 then operates over contact 5 of relay 710 and contact 7 of relay 811 and locks over its 7th contact. Relay 706 opens the circuit of relay 608 at its third contact but relay 608 is held to ground at contact 6 of relay 710. Over contact 2 of relay 816, contact 9 of relay 706, and contact 6 of relay 611, and the wiper of the junction finder, ground is connected to terminal 605 and wire 505 of the calling line. Over contact 6 of relay 818, contact 6 of relay 816, contact 6 of relay 706 and contact 8 of relay 807, relay 818 is connected to wiper 523 of finder 520. Over contact 4 of relay 706, contact 4 of relay 726, contact 9 of relay 717, contact 11 of relay 816, contact 1 of relay 818 and contact 4 of relay 807 a driving circuit is closed for magnet 525 of finder 520. When its wipers are resting on the terminals of the calling line, relay 818 operates and opens the drive at its first contact, closing also a driving circuit for magnet 525 of finder 530 over its second contact and contact 6 of relay 807. Over contact 5 of relay 706 and wiper 705 of the selector 700, battery is connected to the steer wire 506 of the called line. Over contact 4 of relay 717, contact 3 of relay 818, contact 10 of relay 807, relay 717 is connected to wiper 533 of finder 530 and when the wipers of this finder are resting on the terminals of the called line, relay 717 operates. Relay 717 opens the drive at its 9th contact, locks at its 3rd contact and connects relay 710 to the negative leg of the called line over contact 8 of relay 811, contact 2 of relay 710, contact 6 of relay 717, contact 10 of relay 725, and contact 2 of relay 809. Relay 710 remains held to ground at the subset.

It will be thus seen that a by-path connection between subscriber 361 and subscriber 352 has now been prepared, for at B1 the wipers of finder 520 are resting on the terminals of the calling line and the wipers of finder 530 are resting on the terminals of the wanted line.

Hearing no tone, the operator then throws the ring key, which connects strong battery to the positive leg. This operates relay 809 at A, which disconnects relay 701 from the line and connects strong battery through relay 823 to the positive leg of the tandem junction at its 8th contact. Relay 809 at B1 operates, disconnects relay 701 as before, and connects the negative leg of the tandem junction to both legs of the subscriber's line over contact 1 of relay 811, contact 1 of relay 809 and contact 1 of relay 725, and over contact 3 of relay 809, and contact 3 of relay 725 respectively. We now have a direct path between ground at the bell of the subset and the ring of the operating cord, and grounded ringing is applied, thus operating the subscriber's bell. Relay 823 at A holds in series with relay 809 at B1 and keeps relay 710 operated. A relay in the operating cord holds in series with relay 809 at A keeping the supervisory lamp alight. When the key is restored, relay 809 at A keeping the supervisory lamp alight. When the key is restored, relay 809 at A releases followed by relay 809 at B1, and relay 710 at B1 is reconnected to the calling line.

In the first silent period after the subscriber has removed his receiver, relay 710 is deprived of its holding ground and releases, removing ground from the positive leg of the tandem junction (and preventing any possible reoperation of relay 809) and releasing relay 823 at A. Relay 823 drops relay 710 which removes ground from the positive leg of the main junction and puts out the supervisory lamp at D. On the release of relay 710 at B1, a circuit is closed for relay 508 in the link over contact 4 of relay 706, contact 4 of relay 726, contact 8 of relay 717, contact 3 of relay 710, contact 8 of relay 816 and contact 12 of relay 807. Relay 508 operates and locks over contact 10 of relay 508, contact 4 of relay 519, contact 1 of relay 540, contact 1 of relay 511, contact 6 of relay 507, to ground at key 510. The calling and called parties are now connected together through condensers over contacts 5 to 8 of relay 508 and their lines are busied at contacts 4 and 9 of relay 508. On the release of relay 710, the circuit in which relay 608 in the junction has been holding is opened at contact 6 of relay 710 and this relay releases.

When the supervisory lamp goes out the operator knows that the call has been established and will remove both plugs. When this has been done battery is removed from both legs and relay 701 at A releases per-

manently. Relay 701 releases relay 701 at B1 and relay 802 at A. Relay 701 at B1 releases relay 802 at that exchange. On the release of relay 802 at A relays 611, 706, 708, 724, 725, 726 and 733 release and a homing circuit for the selector, controlled by relay 822 is closed over wiper 715, interrupter spring of magnet 702, contact 6 of relay 802, contact 8 of relay 725, contact 1 of relay 710, and contact 1 of relay 805. Relay 703 also operates until the switch is home over contact 4 of relay 701 and operates relay 827. Relay 827 at its 6th contact prevents any junction finder from operating. When the selector has returned to its home position and relays 803 and 827 have released, the register is again normal and may be seized for another call. Similarly, at B1 when relay 802 restores, relays 611, 706, 708, 816, 717 and 818 restore, the selector returns to its home position and the register is again normal.

The talking connection between the two subscribers is now established over a link at B1 and is completely under their control. When either party replaces his receiver, relay 519 or relay 540 operates to the ground at the subset and, if this ground persists for a sufficient time, releases relay 508 at contact 4 of relay 519, or contact 1 of relay 540. With relay 508 restored, the connection is broken down and the link is again normal and rendered available for another call by the opening of contact 3 of relay 508. The subscribers are unbusied at the 4th and 9th contacts of relay 508.

Call III

The establishment of a call from subscriber 361 to subscriber 474 will now be described.

In the final connection, this call involves offices B1 and B2 and tandem junctions between B1 and A and between A and B2. After the establishment of the call, the operator will release the junction between D and A which has been used. The circuits involved in this call are indicated in Fig. 15.

Subscriber 361 originates the call which is received by the operator at D. The operator inserts the set-up plug, associates the register at A, and proceeds to dial the digits of the wanted number. Relay 701 responds to the impulses of the first digit, 4, and steps the selector, and relays 703 and 827 operate. At the end of the digit, the selector wipers are resting on the terminals of line 74 (not the wanted line, which is on exchange B2) and when relay 703 releases a circuit is closed for relay 734 over contact 2 of relay 703, contact 13 of relay 724, wiper 716, terminal of line 74, contact 14 of relay 724, upper winding of relay 734, contact 6 of relay 814, and contact 4 of relay 802. Relay 734 locks over its 4th contact and operates relay 724 at its 5th contact, and relay 724 operates relay 731. Relay 731 connects battery to the steer

100

105

110

115

120

125

130

wire of the calling tandem line as before, but relay 726 does not operate since it is connected only to the lines in the "4" group over contact 2 of relay 734. When relay 703 has restored relay 827 releases, followed by relay 731 and relay 726 is disconnected from these lines. Relay 724 also closes a driving circuit for the selector 700, controlled by relay 822 at contact 4 of relay 724. Wiper 704 of the selector 700 is connected to wiper 716 over contact 3 of relay 726 and contact 12 of relay 724. All disengaged tandem lines, in whatever group, have 20 ohms to battery on their terminals to which wiper 704 has access over contact 3 of relay 1101 and contact 4 of relay 1102. The terminal 709 of line 61, that is, the line immediately following the tandem lines, is connected to battery over contact 2 of relay 724. The terminal of this line served by brush 716 is connected to relay 805 over contact 1 of relay 813, contact 2 of relay 814, and contact 2 of relay 805. The terminals of the tandem lines served by brush 716 in the required group only, that is, with typical wiring as shown, lines 57, 58 and 59, are connected to relay 708 over contact 3 of relay 734 and contact 4 of relay 708. The selector is now searching for a free tandem line in the 4 group. At contacts 14, 8 and 3, relay 724 disconnects relays 734, 708 and 813 and 814 respectively from terminals over which wiper 716 may pass during this search.

If all the lines in the group are engaged, the selector hunts until the terminals of line 61 are reached, then relay 805 operates, locks and closes a tone producing circuit at its 4th contact. This informs the operator either that she has dialed incorrectly or that there is no tandem line available and she will release the registers by removing the set-up plug. If she is satisfied that the number has so far been correctly dialed, she will inform the calling party that there is no outlet available; otherwise she will dial again.

Assuming that there is a free tandem line in the required group, relay 708 operates as soon as its terminals have been reached. Relay 708 opens the drive, locks, and operates relay 725. At contact 7 of relay 725 ground is placed on wiper 704 to operate the cut off relay such as relay 1101 of the tandem line which has been seized. Relay 725 connects weak battery to the positive leg of this line at its second and 5th contacts to operate relay 217 at B2, and strong battery to the negative leg at the 9th contact of relay 725 to associate the register at this exchange.

When relay 708 at A operates, a circuit is closed for relay 816. Relay 816 locks and at its 13th contact closes a circuit in which relay 807 will operate if the first-choice link is engaged and relay 805 will operate if both links are engaged.

Assuming that a link is available at A, the

operator on hearing no tone will proceed to dial the second digit 7. Relay 701 at A responds and repeats the impulses to relay 301 at B2 and the selector at B2 is driven 7 steps and comes to rest with its wipers on the terminals of line 52. When relay 303 releases a circuit for relay 414 is closed over contact 2 of relay 303, wiper 316, contact 4 of relay 413, winding of relay 414, contact 6 of relay 308 and contact 4 of relay 402. Relay 414 operates, locks over its 5th contact and closes a driving circuit for the selector 300, controlled by relay 422 over its first contact. At contact 6 of relay 414, relay 308 is connected to the terminal of line 60, that is, the line immediately preceding the 70's group. At contact 2 of relay 414, relay 405 is disconnected from a terminal over which the selector 300 is about to pass. When the selector 300 reaches the terminals of line 60, relay 708 operates over contact 2 of relay 303, wiper 316, contact 6 of relay 414, contact 4 and winding of relay 308, and contact 4 of relay 402, locks out over its 5th contact, and opens the drive at its 8th contact.

The operator then dials the third digit. Relay 301 at B2 responds to the impulses and steps the selector.

It will be observed that 71, 72, 73, 74 and 75 are the only lines available in the 70's so that to dial 76 or more would be an irregular action. If 76 or more has been dialed in error, relay 405 operates as soon as line 51 is reached, over contact 7 of relay 308, wiper 316, contact 4 of relay 414, contact 2 and winding of relay 405, contact 7 of relay 306 and contact 4 of relay 402, and the operator hears tone. Unless she is satisfied that the number has been correctly dialed she will release the registers and dial again.

Assuming that 4 has been correctly dialed, the selector is positioned on the terminals of line 74, that is, of the wanted line. During the train of impulses relays 303, 427 and 404 have been operated and when relay 427 releases the line is tested and, if free, relays 310 and 306 at B2 operate, followed by relays 823, 710 and 706 at A, and the operator will ring the wanted party.

When relay 306 at B2 operates, battery is connected to the steer wire 105 of the called line over contact 4 of relay 306 and wiper 305 of the selector 300 and relay 317 is connected to wiper 205 of the finder 210 in the junction which has been taken into use over contact 4 of relay 317, contact 1 of relay 416, contact 8 of relay 306, and contact 5 of relay 211. At contact 3 of relay 306 a drive circuit is closed for this finder over contact 8 of relay 317, contact 9 of relay 416, contact 9 of relay 211, and contact 8 of relay 208. When the finder reaches the terminals of the wanted line, relay 317 operates, locks over its third contact and opens the drive at its 8th contact.

- When relay 706 at A operates, the wipers of finder 520 and finder 530 in the link are positioned on the terminals of the calling and called tandem junctions, respectively.
- 5 Also when relay 706 operates a circuit is closed for relay 507 in the link over contact 14 of relay 807, contact 3 of relay 816, contact 2 of relay 706, contact 5 of relay 611, contact 9 of relay 608, and contact 2 of relay 620.
- 10 When relay 818 operates a circuit is closed for relay 511 in the link over contact 7 of relay 511, contact 18 of relay 807, contact 7 of relay 818, contact 5 of relay 816 and contact 11 of relay 724. Both these relays operate 15 and lock over their first and sixth contacts respectively, contact 1 of relay 508, contact 16 of relay 807 and contact 4 of relay 818. At contact 2 of relay 507 and contact 5 of relay 511 circuits are closed for relays 519 and 540.
- 20 It will thus be seen that a by-path connection between subscriber 361 and subscriber 474 has now been prepared, for at B1 the wipers of the junction finder 610 are resting on the calling line, at A the wipers of finder 25 520 are resting on the terminals of this junction and the wipers of finder 530 are resting on the terminals of a tandem junction, the wipers of whose finder 210 at B2 are resting on the terminals of the wanted line.
- 20 Hearing no tone, the operator will ring the wanted subscriber. In the first silent period after he has answered, relay 310 at B2 releases, followed by 823 and 710 at A, putting out the supervisory lamp at D.
- 35 When relay 310 at B2 releases, a circuit is closed for relay 208 in the junction over contact 3 of relay 306, contact 7 of relay 317, contact 3 of relay 310, contact 4 of relay 416 and contact 8 of relay 211. When relay 40 710 at A releases, a circuit is closed for relay 508 in the link over contact 4 of relay 706, contact 4 of relay 726, contact 8 of relay 717, contact 4 of relay 710, contact 8 of relay 816, and contact 12 of relay 807, and relay 45 508 locks over its 10th contact and contact 3 of relay 519 and contact 5 of relay 507 in parallel with contact 2 of relay 511 and contact 2 of relay 540 to ground at key 510. Relays 507 and 511 hold to ground at contact 50 2 of relay 508. Also when relay 710 at A releases, the circuit of relay 608 in the junction is opened at contact 7 of relay 710. Relays 519 and 540 are still held by ground at contact 4 of relay 818 and contact 11 of relay 55 724 respectively. Also when relay 710 releases the circuit of relay 725 is opened at contact 5 of relay 710 and this relay restores, removing strong battery from the negative leg of the tandem junction at its 9th contact and thus releasing the register at B2. On the release of relay 301 at B2, relays 303 and 427 operate and at contact 4 of relay 427 a holding circuit for relay 208 in the junction 60 57 is maintained until relay 211 releases and reconnects relay 208 to ground at contact 1 of relay 203.
- When relay 508 in the link operates a direct connection between the calling and called tandem junctions is established over contacts 5 to 8 of relay 508 and these junctions are busied by ground at the 4th and 9th contacts of relay 508 respectively. Weak battery through coil 516 operates relay 617 at B1 which in turn operates relay 602 and relay 602 connects the calling subscriber's line to the tandem junction. Assuming the calling subscriber is still on the line, relay 603 at B1 remains unoperated and a holding circuit for relay 519 at A is provided over contact 5 of relay 603. Similarly, weak battery through coil 517 at A operates relay 217 at B2 which in turn operates relay 202 and the connection between the calling and called subscribers is now complete. Assuming the 80 called subscriber is still on the line, relay 203 at B2 remains unoperated and closes a holding circuit for relay 540 at A.
- On seeing the supervisory lamp go out the operator will remove both plugs, releasing 90 the register at A and the junction between A and D.
- The talking connection is now established over a link at A and is completely under the control of the calling and called parties. 95 When one of these hangs up, say for example the calling party, relay 603 at B1 operates, relay 519 at A releases and strong battery is connected to the positive leg of the tandem junction to B2 over contact 3 of relay 507 100 and contact 2 of relay 519. This battery operates relay 218 at B2, which operates relay 203, which in turn releases relay 540 at A. With relays 519 and 540 both released, the locking circuit of relay 508 is 105 opened and if this condition persists relay 508 releases. Relay 508 releases relays 507 and 511 at its second contact and the link is completely released. When battery is removed from the tandem junctions at contacts 110 6 and 7 of relay 508 the junctions at B1 and B2 are both released.
- Call IV*
- The establishment of a call from subscriber 361 to subscriber 3467 will now be described.
- In the final connection, this call involves offices B1 and C and a tandem junction between them. After the establishment of the 120 call the operator will release the junctions between D and A and between A and B1 which have been used. The circuits for this call are to be arranged as shown in Fig. 16.
- Subscriber 361 originates the call and it 125 is received by the operator at D. The operator inserts the set-up plug, associates the register at A, dials, relays 733, 724, 726, 708 and 725 operate, and the register at B1 is associated with the tandem junction already 130

taken into use. The operator then dials 4. At the end of the digit, relay 734 at B1 operates, followed by relay 724, and the selector searches for a disengaged tandem junction in the "4" group, that is, the group giving access to office C. If a free line is found, relay 708 and 725 operate and the register at C is seized and associated with this line. The operator then dials 6. The impulses 10 are repeated from relay 701 at A to relay 701 at B1 and thence to relay 301 at C, and the selector at this office is stepped to the terminals of line 51.

At the end of the digit, relay 303 releases 15 and a circuit is closed for relay 413 over contact 2 of relay 303, wiper 316, contact 3 of relay 414, winding of relay 413, contact 6 of relay 308 and contact 4 of relay 402. Relay 413 operates and locks over its second 20 contact and at its third contact connects relay 308 to the terminal of line 50, that is, the terminal immediately preceding the 60's. When relay 427 releases, a driving circuit is closed for the selector 300, controlled by 25 relay 422, at contact 3 of relay 427. When the wipers reach the terminals of line 50 relay 308 operates over contact 2 of relay 203, wiper 316, contact 3 of relay 413, contact 4 and winding of relay 308 and contact 30 4 of relay 402, locks over its 5th contact and opens the drive at its 8th contact. Relay 416, operates and locks and a test is made for a disengaged link.

The operator then dials the final digit 7 35 and the selector 300 at C is stepped on to the terminals of the wanted line. At the end of the digit the line is tested, relay 310 operates at C followed by relays 823, 710 and 706 at B1 and relays 823, 710 and 706 at A, and the 40 supervisory lamp lights. If the line is free relay 306 at C operates, and the wipers of the junction finder are positioned on the terminals of the wanted line. When relay 706 at B1 operates the wipers or finder 520 and 45 finder 530 in the link are positioned on the terminals of the calling line and called tandem junction, respectively. Also when relay 818 at B1 operates a circuit is closed for relay 511 in the link over contact 7 of relay 50 50 511, contact 18 of relay 807, contact 7 of relay 818, contact 5 of relay 816 and contact 11 of relay 724. Relay 511 locks over contact 6 of relay 511, contact 1 of relay 508, contact 16 of relay 807 and contact 4 of relay 818, 55 and relay 540 operates over contact 5 of relay 511, contact 18 of relay 807, contact 7 of relay 818, contact 5 of relay 816 and contact 11 of relay 724.

It will thus be seen that a by-path connection between subscriber 361 and subscriber 3467 has now been prepared, for at B1 the wipers of finder 520 are resting on the terminals of the calling line, and the wipers of finder 530 are resting on the terminals of a 60 tandem junction the wipers of whose finder

210 at C are resting on the terminals of the wanted line.

On receipt of the lamp signal, and hearing no tone, the operator will ring the wanted subscriber. In the first silent period after he has answered, relay 310 at C releases, followed by relays 823 and 710 at B1 and relays 823 and 710 at A and the supervisory lamp at D goes out. When relay 310 at C releases, relay 208 in the junction operates. When relay 710 at B1 releases relay 508 in the link 70 operates and locks over contact 10 of relay 508, contact 2 of relay 511 and contact 2 of relay 540, to ground at key 510. Also when relay 710 at B1 releases, relay 608 in the junction releases. Similarly when relay 710 at A releases, relay 608 in the junction releases. 75

When relay 508 in the link operates, the calling subscriber is connected to the called tandem junction, weak battery through coil 517 at B1 operates relay 217 at C which operates relay 202 and completes the connection to the called subscriber. Assuming the latter is still on the line relay 203 at C remains unoperated and a holding circuit for relay 540 at B1 is closed at contact 3 of relay 203. 80

On seeing the supervisory lamp go out, the operator removes both plugs, releasing the 85 register at A. When relay 725 releases, battery is removed from the negative leg of the tandem junction and the register at B1 is released in a similar manner.

The talking connection is now established 90 over a link at B1 and is completely under the control of the calling and called parties. Should the called party hang up first, relay 203 at C will operate, followed by the release of relay 540 at B1 and if this condition persists, relay 508 will release and break down the connection. If, on the other hand, the calling party hangs up first, relay 519 at B1 95 operates and at its first contact, connects strong battery to the positive leg of the tandem junction operating relay 218 at C. Relay 218 operates relay 203 which releases relay 540 at B1 and after an interval relay 508 releases and breaks down the connection as before. 100

Call V

The establishment of a call from an urban subscriber to subscriber 474, will now be described. The circuits are to be arranged as 110 shown in Fig. 17.

The operator receives the subscriber's requirements and originates a call to the rural system by inserting the calling plug of her regular cord and the set-up plug of her operating cord in the jacks of a disengaged junction. The register at A is associated with this junction and relay 701 therein responds to the impulses dialed. At the end of the first digit, relays 804, 734 and 724 op- 125 130

erate and the selector is caused to hunt for a free tandem line in the "4" group. Relay 708 operates as soon as one is found, opens the drive and operates relay 725, which in turn 5 operates the cut-off relay 1101 of the tandem line and associates the register at B2 with it. The second and third digits position the selector at B2 on the terminals of the wanted line which is then tested. Relay 310 at B2 10 operates, followed by relays 823, 710 and 706 at A. The finder of the main junction 610 taken into use is positioned on the terminals of the tandem line. If the called line is free, relay 306 at B2 also operates, and the finder 15 of the tandem junction 210 is positioned on the terminals of the wanted line. At contact 2 of relay 706 at A a circuit is closed for relay 620 in the junction over contact 11 of relay 724, contact 4 of relay 816, contact 2 of 20 relay 706 and contact 5 of relay 611.

It will be seen that a by-path connection between the urban operator and subscriber 474 has now been prepared, for at A the 25 wipers of the junction finder 610 are resting on the terminals of the tandem junction, the wipers of whose finder 210 at B2 are resting on the terminals of the wanted line.

Hearing no tone, the operator will ring 30 the wanted subscriber. In the first silent period after he has answered, 310 at B2 releases, followed by relays 823 and 710 at A and the supervisory lamp at D is put out. When relay 310 at B2 releases a circuit is 35 closed for relay 208 in the junction at B2 over contact 3 of relay 306, contact 7 of relay 317, contact 3 of relay 310, contact 4 of relay 416 and contact 8 of relay 211. When relay 710 at A releases a circuit is closed for relay 608 over contact 4 of relay 706, contact 4 of 40 relay 726, contact 8 of relay 717, contact 3 of relay 710, contact 7 of relay 816 and contact 9 of relay 611. Also when relay 710 at A releases, the circuit of relay 725 is opened and this relay restores and releases the register at 45 B2. When relay 211 at B2 restores, relay 208 is left locked over contact 3 of relay 208, contact 7 of relay 211, and contact 1 of relay 203. When relay 608 at A operates, relay 620 locks 50 over its second contact and contact 9 of relay 608 and this ground also operates relay 603 over contact 2 of relay 602, contact 2 of relay 608, and contact 4 of relay 618.

On seeing the supervisory lamp go out, the 55 operator will remove the set-up plug, releasing the register at A. When relay 611 restores, relay 608 is left locked over its third contact, contact 8 of relay 611, contact 2 of relay 603 and contact 7 of relay 620. The 60 regular plug is still in the talk jack so that relays 617 and 602 operate in turn at A followed by relays 217 and 202 at B2 and a direct connection is established between the two subscribers. Positive supervision is provided 65 between the called subscriber and the oper-

ator precisely as in a call originated from a rural subscriber.

What is claimed is:

1. In a telephone system a calling line at one office an operator's position at another office, a called line at a third office, a junction line, means including said junction line for automatically extending a connection from said calling line to said operator's position, means under the control of the operator at 10 said position, operable over said junction line for automatically selecting said third office and said called line, an alternative path between said calling and called lines, means responsive to the selection of said third office, 15 to prepare said alternative path and means responsive to the establishment of said alternative path to release said junction line.

2. In a telephone system, a calling line, an operator's position at a distant office, a called line, a plurality of junction lines, means including said junction lines for automatically extending a connection from said calling line to said operator's position, means under the control of the operator at said position operable over said junction lines for automatically selecting the office at which said called line is located and said called line, means responsive to the selection of the office at which said called line is located to prepare 20 an alternative path between said calling and called lines and means responsive to the completion of said alternative path to release said junction lines.

3. In the telephone system, a plurality of offices associated in a network, a plurality of junction lines extending through said plurality of offices, a calling line at one of said offices, an operator's position at another of said offices, a called line, means including said junction lines for automatically extending a connection from said calling line to said operator's position, means under the control of the operator at said position operable over one or more of said junction lines for automatically selecting the office in which said called line is located and said called line, an alternative path between said calling and called lines, said alternative path being located in that one of said plurality of offices which has access both to said one office and to the office in which said calling line is located and which is farthest from the office at which the operator's position is located in the network, means to prepare said alternative paths, and means responsive to the completion of said alternative path to release those of said junction lines used in selecting the office in which said alternative path is located.

4. In the telephone system, a plurality of offices associated in a network, a plurality of junction lines extending through said plurality of offices, a calling line at one office, an operator's position at another office, a called line, means including said junction lines for

automatically extending a connection from said calling line to said operator's position, means under the control of the operator at said position operable over one or more of said junction lines for automatically selecting the office in which said called line is located and said called line, an alternative path between said calling and called lines, said alternative path being located in that one of 5 said plurality of offices which has access both to said one office and to the office in which said calling line is located and which is farthest from the office at which the operator's position is located in the network, means 10 15 to prepare said alternative path and means responsive to the completion of said alternative path to release those of said junction lines used in selecting the office at which said alternative path is located said means for 20 preparing said alternative path being effective whether said calling and said called lines are located in the same or different offices.

5. In a telephone system a calling line at one office, an operator's position at another office, a called line at a third office, a junction line, means including said junction line for automatically extending a connection from said calling line to said operator's position, means under the control of the operator at 25 30 35 40 45 said position, operable over said junction line for automatically selecting said third office and said called line, means responsive to the initiation of said selecting operation to disconnect said calling line from said operator's position, an alternative path between said calling and called lines, means responsive to the selection of said third office to prepare said alternative path and means responsive to the establishment of said alternative path to release said junction line.

6. In a telephone system, a calling line, an operator at a distant office, a called line, a plurality of junction lines, means including said junction lines for automatically extending a connection from said calling line to said operator's position, means under the control of the operator at said position operable over said junction lines for automatically selecting the office at which said called line is located and said called line, means responsive to the initiation of said selecting operation to disconnect said calling line from said operator's position, means responsive to the selection of said office to prepare an alternative path between said calling and called lines and means responsive to the completion of said alternative path to release said junction lines.

7. In a telephone system, a calling line at one office an operator's position at another office, a called line at a third office, a junction line, means including said junction line for automatically extending a connection from said calling line to said operator's position, means under the control of the operator at

said position, operable over said junction line for automatically selecting said third office and said called line, an alternative path between said calling and called lines, means responsive to the selection of said third office to prepare said alternative path, means controlled by the response of the called subscriber to complete said alternative path and to disconnect said called line from said operator's position, and means responsive to the establishment of said alternative path to release said junction line. 70 75

8. A telephone system, a calling line, an operator at a distant office, a called line, a plurality of junction lines, means including said junction lines for automatically extending a connection from said calling line to said operator's position, means under the control of the operator at said position operable over said junction lines for automatically selecting the office at which said called line is located and said called line, means responsive to the selection of said office to prepare an alternative path between said calling and called lines, means controlled by the response of the called subscriber to complete said alternative path and to disconnect said called line from said operator's position and means responsive to the completion of said alternative path to release said junction lines. 80 85 90 95

9. In a telephone system a calling line at one office, an operator's position at another office, a called line at a third office, a junction line, means including said junction line for automatically extending a connection from said calling line to said operator's position, means under the control of the operator at said position, operable over said junction line for automatically selecting said third office and said called line, an alternative path between said calling and called lines, means to automatically disconnect said calling and said called lines from said operator's position and means to render said alternative path effective. 100 105 110

10. In a telephone system, a calling line, an operator's position at a distant office, a called line, a plurality of junction lines, means including said junction lines for automatically extending a connection from said calling line to said operator's position, means under the control of the operator at said position operable over said junction lines for automatically selecting the office containing the called line and said called line, means to automatically disconnect said calling and said called lines from said operator's position and means to establish an alternative talking path between said calling and said called lines. 115 120 125

11. In a telephone system comprising small offices and a main office, said offices radiating from said main office in tandem formation, means for extending a connection from a calling line in any one of said 130

small offices to operator's position in said main office, numerical switching mechanism in said small offices, means under the control of the operator at said position for operating said numerical switching mechanism to extend a connection from said position to a called line, means responsive to the completion of said connection for automatically establishing an alternative path between said calling and said called lines and means for thereupon releasing said numerical switching mechanism.

12. In a telephone system comprising small offices and a main office, said small offices radiating from said main office in tandem formation, means for extending a connection from a calling line in any one of said small offices to said operator's position in said main office, numerical switching mechanism in each of said small offices, means under the control of the operator at said position for operating a plurality of said switching mechanisms in turn, to extend a connection from said position to a called line, means responsive to the completion of said connection for automatically establishing an alternative path between said calling and said called lines and means for thereupon releasing said numerical switching mechanism.

13. In a telephone system comprising small offices and a main office, said offices radiating from said main office in tandem formation, means for extending a connection from a calling line in any one of said small offices to said operator's position in said main office over one path, means under the control of the operator at said position for selecting a wanted line at any one of said small offices over a second path, means for automatically completing an alternative path between said calling line and said called line, means responsive to the initiation of said selecting operation to open said first path to said position and means controlled by the response of said wanted subscriber for opening said second path to said position.

14. In a telephone system a plurality of offices associated in a network, a calling line at one of said offices, an operator's position at a second one of said offices, a called line, junction lines extending between said offices, means for automatically extending a connection from said calling line to said operator's position over one path, means under the control of the operator at said position for automatically selecting the office in which said called line is located and said called line over a second path, an alternative path between said calling and called lines, said alternative path being located in that one of said plurality of offices which has access to both said one office and to the office in which said called line is located and which is farthest from the office at which said operator's

position is located in the network, means responsive to the initiation of said selecting operation to open said first path to said position, means controlled by the response of said wanted subscriber for opening said second path to said position and means responsive to the completion of said alternative path to release said selecting means.

15. In a telephone system a plurality of small offices, a main office, junctions common to said small offices for connecting said offices with said main office, a registering mechanism in each small office, means to control said registering mechanisms in tandem from said main office to set up a connection from one small office to another and means cooperating with one or more of said registering mechanisms to automatically complete a talking circuit between said offices independent of said registering mechanism.

16. In a telephone system, a plurality of small offices, a main office, junctions common to said small offices, means to establish a connection from a calling line to said main office over said junctions, a registering mechanism in each small office, means to control said mechanisms in tandem from said main office to set up a connection from said main office to a called line and means responsive to the establishment of said connection for opening the connection between said calling line and said main office and for automatically preparing an alternative path between said calling and said called lines.

17. In a telephone system a plurality of small offices, a main office, junctions common to said small offices, means to establish a connection from a calling line to said main office over said junctions, a registering mechanism in each small office, means to control said registering mechanisms in tandem from said main office to set up a connection from said main office to a called line, means responsive to the establishment of said connection for opening the connection between said calling line and said main office and for automatically preparing an alternative path between said calling and said called lines, and means controlled by the response of the called line to complete said alternative path and to automatically open the connection from said main office to said called line.

18. In a telephone system a plurality of small offices, a main office, junctions common to said small offices, means to establish a connection from a calling line to said main office over said junctions, a registering mechanism in each small office, means for controlling said registering mechanisms in tandem from said main office to set up a connection from said main office to a called line, means responsive to the establishment of said connection for opening the connection between said calling line and said main office and for automatically preparing an alternative

path between said calling and said called lines, means controlled by the response of the called line to complete said alternative path and to automatically open the connection from said main office to said called line, and means responsive to the completion of said alternative path for releasing said registering mechanisms.

19. In a telephone system a plurality of 10 small offices, a main office, junctions common to said small offices, means to establish a connection from a calling line to said main office over said junctions, a registering mechanism in each small office, means to control 15 said registering mechanisms in tandem from said main office to set up a connection from said main office to a called line, an alternative path between said calling and said called lines comprising non-numerical 20 switching mechanisms located in the office farthest from the main office and having access to the offices in which the calling and called lines are located, and means responsive to the establishment of said connection 25 for opening the connection between said calling line and said main office and for automatically preparing said alternative path.

20. In a telephone system a plurality of 30 small offices, a main office, junctions common to said small offices, means to establish a connection from a calling line to said main office over said junctions, a registering mechanism in each small office, means for controlling 35 said registering mechanisms in tandem from said main office to set up a connection from said main office to a called line, an alternative path between said calling and said called lines comprising non-numerical switching mechanisms located in the office 40 farthest from the main office and having access to the offices in which the calling and called lines are located, means responsive to the establishment of said connection for opening the connection between said calling 45 line and said main office and for automatically preparing said alternative path, and means controlled by the response of the called line to complete said alternative path and to automatically open the connection 50 from said main office to said called line.

21. In a telephone system a plurality of 55 small offices, a main office, junctions common to said small offices, means to establish a connection from a calling line to said main office over said junctions, a registering mechanism in each small office, means for controlling 60 said registering mechanisms in tandem from said main office to set up a connection from said main office to a called line, an alternative path between said calling and said called lines comprising non-numerical switching mechanisms located in the office farthest from the main office and having access to the offices in which the calling and 65 called lines are located, means responsive to

the establishment of said connection for opening the connection between said calling line and said main office and for automatically preparing said alternative path, means controlled by the response of the wanted subscriber to complete said alternative path and to automatically open the connection from said position to said called line, and means responsive to the completion of said alternative path for releasing said registering 70 mechanisms.

22. In a telephone system a plurality of 75 small offices, a main office, said small offices being connected in tandem formation to said main office, an operator's position at said main office, a calling line, means to automatically extend said calling line to said operator's position, automatic switches at said 80 small offices, means under the control of said operator's position to operate said switches in a number of said small offices in tandem to extend a connection to a called line, means effective when said connection is extended to the office in which the called line is located to prepare an alternative path between said calling and said called lines, said alternative path including only those offices lying between the calling and the called lines in the tandem formation and means for thereupon releasing 85 said automatic switches over which the connection was set up.

23. In a telephone system a plurality of 90 small offices, a main office, said small offices being connected in tandem formation to said main office, an operator's position at said main office, a calling line, means to automatically extend said calling line to said operator's position, a registering mechanism at each of said small offices, a set of switching devices at each of said small offices, means under the control of said operator's position to operate said registering devices in a number of said small offices in tandem to extend a connection to a called line, means including 95 one of said sets of switching devices for co-operating with said registering mechanisms when the connection over all of said registering mechanisms has been completed, to complete an alternative path between said calling and said called lines, said alternative path including only those offices lying between the calling and the called lines in the 100 tandem formation.

24. In a telephone exchange system, a plurality of small offices, a main office, said small offices being connected in tandem formation to said main office, an operator's position at said main office, a registering device at each of said small offices, a calling line, a called line, a set of switching devices in each of said small offices, means including a switching device of one group in each said set of switching devices for extending said calling line to said operator's position, means under the control of said operator's position for oper- 105 110 115 120 125 130

ating said registering devices in a number of small offices in tandem to extend a connection from said position to said called line, means including a switching device of another group 5 in said set of switching devices for cooperating with said registering device for preparing an alternative path between said calling and said called line, said alternative path including only those offices lying between the 10 calling and the called lines in the tandem formation.

25. In a telephone exchange system, a plurality of small offices, a main office, said small offices being connected in tandem formation 15. to said main office, an operator's position at said main office, a registering device at each of said small offices, a calling line, a called line, a set of switching devices in each of said small offices, means including a switching device of one group in each said set of switching devices for extending said calling line to said operator's position, means under the control of said operator's position for operating said registering devices in a number 20 of small offices in tandem to extend a connection from said position to said called line, means including one of the switching devices in the other group in said set of switching devices for cooperating with said registering 25 mechanism and one of said switching devices in said first group to prepare an alternative path between said calling and said called line, said alternative path including only those offices lying between the calling 30 and the called lines in the tandem formation, each said switching device of said other group comprising two finder switches, one of which is adapted to position itself in accordance with the position of the switching device of 35 said one group in the same office and the other of which is adapted to position itself in accordance with the setting of the registering mechanism in that office.

40 In witness whereof, I hereunto subscribe
45 my name this 19th day of February, 1930.
LESLIE BAINES HAIGH.
